AERIAL TOY

Victor Paul Blackwell, 1067 Brook Ave., Cincinnati, Ohio

Filed Mar. 23, 1964, Ser. No. 79,108

Term of patent 14 years

(Cl. D34—15)

FIGURE 1 is a top plan view of the aerial toy with the parachute portion of the device shown in dotted lines in the folded condition.

FIGURE 2 is a bottom plan view thereof.

FIGURE 3 is a side elevational view thereof.

FIGURE 4 is a perspective view on a reduced scale with the parachute portion of the toy shown in dotted lines in the extended condition.

The essential features of my design reside in the portions shown in full lines.

I claim:

The ornamental design for an aerial toy, as shown and described.
